UNITED STATES PATENT OFFICE.

VICTOR EUGENE LOUIS CHAUVENTTE, OF PARIS, FRANCE.

PRINTING-MACHINE.

1,398,360.

Specification of Letters Patent. Patented Nov. 29, 1921.

Application filed July 1, 1920. Serial No. 393,354.

To all whom it may concern:

Be it known that I, VICTOR EUGENE LOUIS CHAUVENTTE, citizen of the Republic of France, residing at 21 Rue Ganneron, Paris, in the 5 Republic of France, have invented new and useful Improvements in Printing-Machines, (for which I have filed an application in France, July 18th, 1919,) of which the following is a specification.

10 This invention has for its object a printing machine adapted to print upon wooden panels or any other similar materials which are not sufficiently flexible and cannot be carried along in rotary movement around a 15 cylinder. Printing is effected in the machine by transfer on an intermediate cylinder provided with a rubber coating. Important features of the improved machine are the operating device for the bed and 20 preventing any movement of the panel during the printing operation.

In the accompanying drawings given by way of example:

Figure 1 is an end elevation of the improved machine.

Fig. 2 is a corresponding side elevation.

Fig. 3 is a section view of the means used for maintaining the panel to be printed upon the bed.

Fig. 4 is a side view of a detail of the machine.

The printing plate P is carried by the printing cylinder A which is driven by the intermediate cylinder C through the medium of toothed wheels L and O. The cylinder C is itself driven by the belt pulley U through the reducing gearing S, T, R, Q.

By reason of the porosity of wood, it is necessary to effect a strong inking which will 40 permit the employment of a thick ink and for that reason an inking surface having an area twice that of the printing surface, i.e. the plate P carrying the lithographic design, has been provided. The plate P extends thus over one third only of the surface of the cylinder A which in its rotation brings the plate in contact first with the wetting rollers M and then with the inking rollers E. The cylinder continuing to re-

50 volve, the printing plate is brought into contact with the rubber coating or blanket B provided on the intermediate cylinder C. The design is thus transferred onto the rubber cylinder and in the rotation of the latter

transferred again from that cylinder onto 55 the wood panel placed upon the bed D.

The bed D is reciprocated horizontally by the following means. In its operative or printing stroke, it is driven by two toothed sectors F which extend over one third of 60 the circumference of the cylinder C and mesh with two racks V provided on the sides of the bed. When the toothed sectors abandon the racks, the bed is no longer actuated and it abuts against dampening springs not 65 shown and stands still. At this time, another toothed sector G provided on the cylinder C and forming a prolongation of one of the toothed sectors F but located in a different transverse plane, engages with a 70 pinion H which is in mesh with a pinion I keyed on the same shaft as a central pinion J which is itself in engagement with a longitudinal rack K secured under the bed D. The latter is thus brought back to its origi- 75 nal position.

The bed will then stand still until the sectors F engage again with the racks V, i.e. during the last third of the revolution of cylinder C. This interval is used for 80 placing the wood panel in position on the bed. The panel is maintained against three stop pins: two at the end and one on the side.

As it is important to rigidly secure the 85 panel upon the bed so as to prevent any relative movement of said member during the printing operation, the following pneumatic device is provided. The bed D is hollow and has a perforated top wall. It is connected by a valve W¹ to a flexible pipe Y in communication with a tank X in which vacuum is produced by a pump operated by the driving mechanism of the machine. The valve W¹ is operated as follows: 90

When the panel to be printed has been placed in position upon the bed, and when said bed begins to move to the left (Figs. 1 and 3) the roller Z¹ is lifted by a runway Z rigidly secured to the frame of the machine. The valve W¹ is thus lifted also and the bed is set in communication with the vacuum tank X, and the panel is held on the bed by atmospheric pressure. When the printing is effected, the bed at the end 100 of its stroke actuates a second valve W² which is opened by running against the frame of the machine; the air is then al- 105

lowed to enter the bed, so that the panel is freed. At the same time, the roller Z' having run along the whole length of the runway Z, leaves said runway and falls back 5 and the valve W¹ is closed.

Furthermore, when the bed begins to run rearward, a boss 1 provided on the end of the cylinder C comes into contact with a roller 2 which is pushed downward and operates a lever 4 pivoted on a fixed axis 3 connected to the frame of the machine; the piston 6 is thus moved upward, compressing the spring 8 inside a box 7 secured also to the frame of the machine; the lever 10 is caused to pivot about the fixed axis 11 and a small steel rod 12 is lowered and engages with the rear end of the panel and holds the same in position while the bed slides under the panel in returning to its original position. The panel then drops upon an inclined plane and slides onto a receiving table.

A similar arrangement is provided at the other side of the machine, and the bosses 1 extend over an arc of 120° on the circumference of the cylinder C. Thus when the rearward movement of the bed is completed, the rollers 2 are freed and the steel rods 12 are lifted, to allow the passage of the next 30 panel to be printed.

Having now described my invention, what I claim as new and desire to secure by Letters Patent is:—

1. A printing machine comprising a rotary printing cylinder, a transfer cylinder, said cylinders running constantly and at the same speed, and being mounted respectively in a fixed position with regard to each other, a reciprocating bed, means for rotating the 35 cylinders, means for reciprocating the bed, a printing surface secured on the printing cylinder and extending over one third of the circumference of the cylinder and an ink table constituted by the remaining two 40 thirds of said circumference and adapted to engage inking rollers suitably disposed.

2. A printing machine comprising a ro-

tary printing cylinder, a transfer cylinder, said cylinders running constantly and at the same speed, and being mounted respectively 50 in a fixed position with regard to each other, a reciprocating bed, means for rotating the cylinders, toothed racks on the bed, toothed sectors on the transfer cylinder in engagement with said racks and adapted to move 55 the bed in one direction, a reversing rack on the bed, a reversing toothed sector on the transfer cylinder and means for operatively connecting the reversing toothed sector to the reversing rack.

3. A printing machine comprising a rotary printing cylinder, a transfer cylinder, said cylinders running constantly and at the same speed, and being mounted respectively 60 in a fixed position with regard to each other, a reciprocating bed, means for rotating the cylinders, toothed racks on the bed, toothed sectors on the transfer cylinder in engagement with said racks and adapted to move 65 the bed in one direction, a reversing rack on the bed, a reversing toothed sector on the transfer cylinder, means for operatively connecting the reversing toothed sector to the reversing rack and pneumatic means for securing the work on the bed.

4. A printing machine comprising a rotary printing cylinder, a transfer cylinder, said cylinders running constantly and at the same speed, and being mounted respectively 70 in a fixed position with regard to each other, a reciprocating bed, means for rotating the cylinders, toothed racks on the bed, toothed sectors on the transfer cylinder in engagement with said racks and adapted to move 75 the bed in one direction, a reversing rack on the bed, a reversing toothed sector on the transfer cylinder, means for operatively connecting the reversing toothed sector to the reversing rack and work controlled pneumatic means for securing the 80 work on the bed.

In testimony whereof I have signed my name to this specification.

VICTOR EUGENE LOUIS CHAUVENTTE.
